UNITED STATES PATENT OFFICE.

OTTO A. HOKANSON, OF WOODSTOCK, ILLINOIS, ASSIGNOR TO WOODSTOCK TYPEWRITER COMPANY, OF WOODSTOCK, ILLINOIS, A CORPORATION OF ILLINOIS.

ESCAPEMENT MECHANISM FOR TYPEWRITERS.

Application filed May 10, 1924. Serial No. 712,181.

This invention relates to mechanism for controlling the platen carriage for letter space movement and has for its object the provision of such mechanism which shall be 5 adaptable both for hand and power actuation, and which shall be of improved construction and operation.

The invention is exemplified in the combination and arrangement of parts shown 10 in the accompanying drawings and described in the following specification, and it is more particularly pointed out in the appended claims.

In the drawings—

15 Fig. 1 is a vertical sectional view of a portion of a typewriting machine showing one form of escapement mechanism comprised in the present invention;

20 Fig. 2 is a section substantially on line 2—2 of Fig. 1;

Fig. 3 is a horizontal section substantially on line 3—3 of Fig. 2;

Fig. 4 is a sectional detail;

25 Fig. 5 is a vertical sectional view showing the power driven line spacing mechanism for operating the escapement mechanism shown in Figs. 1 and 2; and

Fig. 6 is a horizontal sectional view of the line spacing lever connection.

30 As shown in Figs. 1 and 2, the numeral 10 designates the top frame of a typewriting machine, such as the "Woodstock" typewriter. Journaled in the frame 10 is a spindle 11 having a pinion 12 secured thereto 35 and an escapement wheel 13 loosely journaled thereon. The escapement wheel 13 carries spring-pressed dogs 14 which engage the teeth of the pinion 12 and prevent relative rotation of the pinion and escapement 40 wheel in one direction, but permitting relative rotation in the opposite direction.

The pinion 12 meshes with a rack 15 secured to the movable platen carriage, not shown. Extending downwardly from the 45 frame 10 are posts 16 and 17 which carry pivot screws 18. A rocking frame 19 having downwardly extending arms 20 is pivoted on the screws 18. Pivoted on the lower ends of the arms 20 are the 50 arms 21 of a universal bar frame 22. The frame 22 may be oscillated in any usual manner when the type bars are operated. One construction of frame for this purpose, together with its connection with the type 55 bars, is shown in Patent No. 1,276,118.

A dog rocker 23 is pivotally supported by ears 24 which engage pivot screws 25 carried on the posts 16 and 17. The dog rocker 23 has a pair of stop screws 26 which engage a bracket 27 projecting inwardly from the posts 16, thus limiting the oscillation of the dog rocker. Mounted on the dog rocker 23 is a fixed dog 28 which is adjustably carried by a slotted arm 29 and held in its adjusted position by screws 30.

A limber-dog 31 is provided with a slot 32 pivoted on a screw 33 supported by the dog rocker 23. A spring 34 normally urges the limber-dog 31 upwardly and in a clockwise direction, as viewed in Fig. 1. The limber-dog 31 may be slid downwardly by a lever 35 pivotally mounted at 36 on the bracket 27 and having a nosepiece 37 which projects into position above a shoulder 38 on the limber-dog 31. The lever 35 may be 70 operated by a roller 39 carried by a lever arm 40 connected with suitable operating mechanism, such as is commonly employed for tabulating. A spring 40' holds the lever 35 against the roller 39.

It will be seen that when the nosepiece 37 is moved downwardly the limber-dog will be out of engagement with the teeth of the ratchet wheel to release the platen carriage for tabulation. When this occurs the lug 41 on the lower end of the limber-dog will engage a stop 42 on the dog rocker to hold the limber-dog from being rotated about its pivotal support by the spring 34. A reverse lock 43 for the escapement wheel is pivotally mounted at 44 on the dog rocker 23 and is held against a stop 45 by a spring 46.

As shown in Fig. 4, the stop 43 is loosely mounted on the pivot screw 44 so that it has motion not only about the axis of the screw, but has a limited movement in a direction transverse to the axis thereof so that the top end of the stop is free to move laterally away from the face of the escapement wheel 13. The spring 46 not only holds the stop 100 against the screw 45, but also pulls it toward the face of the dog rocker to retain it in alignment with the plane of the escapement wheel.

When the carriage is being returned to begin a new line the rack 15 will move to the left, as viewed in Fig. 1, the view being taken from the rear of the machine. During this movement the pinion 12 will rotate independently of the escapement wheel 13 110

and the stop 43 will positively prevent any reverse rotation of the escapement wheel.

During letter space movement or when the carriage is moved by its spring for tabulation the rack will move to the right, as viewed in Fig. 1, and the movement will be controlled by the escapement wheel 13. The stop 43 will not prevent rotation of the escapement wheel in this direction since the spring 46 will permit the stop to yield to the teeth of the escapement wheel. When the rack is controlled by the dogs 28 and 31 for letter spacing the stop 43 will move with the dog rocker and in case it should strike the lateral face of one of the teeth of the escapement wheel, the lateral yielding movement of the stop will prevent any interference with the oscillation of the dog rocker and the control of the escapement 20 dogs.

The dog rocker 23 is operated from the universal bar 22 by a bracket 47 which engages a screw 48 mounted on the dog rocker. The screw 48 also carries the stop member 45. Whenever the universal bar is moved rearwardly by the type bars the bracket 47 will impart a hammer blow to the screw 48 under the influence of the type bars, thus imparting a rapid action to the control dogs 30 and providing quick movement of the letter spacing parts. The dog rocker is returned after operation of the universal bar by a spring 49 attached at 50 to the dog rocker and having its opposite ends secured to a bar 51 passing through the post 17 and held in adjusted positions by a screw 52. Limit stops for the rocker frame 19 are provided independently of the stops for the dog rocker 23. The stops for the rocker frame 19 comprise a screw 53 carried in the frame 10, the head of the screw being interposed in the path of a flange 54 on the frame 19. The movement in the opposite direction is limited by a screw 55 carried by the frame 19 and arranged to strike the lower face of the frame member 10.

The carriage may be spaced independently of the universal bar 22 for spacing between words or at other times when the type bars 50 are not operated. This spacing movement is performed by power actuated mechanism shown in Fig. 5 and controlled by space levers 56 and 57 shown in Figs. 5 and 6. The power driven mechanism comprises a motor driven gear wheel 58 arranged to mesh with a mutilated gear 59. A pair of rollers 60 and 61 are carried by the lateral face of the gear 59 and a spring 62 engages the lowermost roller tending to rotate the mutilated gear to bring the teeth thereon into mesh with the teeth of the power driven gear 58.

An escapement dog 63 has a stop member 64 thereon interposed in the path of the roller 61 to prevent rotation of the mutilated gear. A plunger bar 65 is pivoted at 66 to

the escapement dog 63 and extends into the path of a lug 67 on the space lever 56. The space levers 56 and 57 carry a space bar 68 and when this bar is depressed the stop 64 will be moved away from the roller 61 permitting rotation of the mutilated gear 59 until it is brought into driving relation with the driving gear 58. Further rotation is then produced by the power driven gear until the teeth of the power driver gear register with a blank portion of the mutilated gear. Rotation is then checked either by the nose 69 of the escapement dog or by the stop 64 depending on whether or not the spacing lever is still depressed.

When the mutilated gear 59 is rotated by the power driven gear the roller 61 strikes a cam face 70 on an actuating lever 71 and depresses the actuating lever. The lever 71 is pivoted at 72 on a cross-bar 73 and is held in its upper position by a spring 74. The rear end of the lever 71 carries a pin 75 which engages a slot 76 on a lever 77 pivoted at 78 on a cross-bar 79. The cross-bar 79 carries a bracket 80 having a lever 81 pivoted at 82 thereon. A pin and slot connection 83 provides operative connection between the levers 77 and 81. The upper end of the lever 81 has a link 84 pivoted at 85 thereon and the opposite end of the link 84 is pivotally connected at 86 to an extension 87 on the dog rocker 23, as shown in Figs. 1 and 2.

It will be apparent that when the space bar 68 is depressed to permit operation of the actuating lever 71 from the power driven mechanism the link 84 will be oscillated forwardly to impart an oscillation to the dog rocker and thus release the escapement wheel for rotation by an amount corresponding to one tooth thereof for each depression of the space bar. The actual operation of the escapement mechanism is performed by the power drive and the force required to depress the space bar is only that necessary to release the stop 64 from engagement with the roller 61.

The space levers 56 and 57 are secured to a rock shaft 88 pivoted in brackets 89 and extending transversely of the frame of the machine. A spring 90 holds the space levers in their uppermost position. The pivot 82 to which the lever 81 is secured is in the form of a rock shaft, as shown in Fig. 6, in order to bring the link 84 near the center of the machine.

The plunger 65 is guided by an angle bar 91 pivotally mounted at 92 on plates 93 at each side of the machine. The plates 93 are pivotally supported at 94 and one of the plates carries a pin 95 which cooperates with a cam groove 96 in a plate 97. The plate 97 is pivoted at 98 and is provided with a hand lever 99 by which it may be rocked upon its pivot 98. Movement of the

lever 99 rearwardly will force the pin 95 downwardly and move the angle bar 91 forwardly to bring the plunger 65 out of registration with the projection 67 on the lever 56. When the parts are in this position operation of the space lever 56 will cause the pin 100 to strike the upper member forming the slot 76 and thus oscillate the lever 77 to produce a letter space movement of the platen carriage.

I claim:

1. In a typewriter, the combination with escapement mechanism, of a universal member for actuating said escapement mechanism, power actuated means for operating said escapement mechanism independently of said universal member, a space lever for controlling said power actuated means and driving connection between said power-actuated means and escapement mechanism separate from said space lever.

2. In a typewriting machine, escapement mechanism comprising a dog rocker, a universal member for moving said dog rocker, power driven mechanism for moving said dog rocker independent of said universal member, a space lever for controlling said power-driven mechanism and operating connection between said power-driven mechanism and dog-rocker separate from said space lever.

3. In a typewriting machine, escapement mechanism comprising a fixed dog, a limber-dog, an escapement member controlled by said dogs, a spring for moving said limber-dog to advanced position when freed from said escapement member, means for moving said limber-dog out of operative position, and a stop for holding said limber dog against movement to advanced position when out of operative position.

4. In a typewriting machine, escapement mechanism comprising an escapement wheel, a fixed dog, a limber-dog, a spring for holding said limber-dog in operative relation with said escapement wheel and for pivotally moving said dog from a retracted to an advanced position relative to said escapement wheel, means for moving said limber-dog out of operative relation with said escapement wheel, and a stop for holding said limber-dog against pivotal movement in its retracted position when out of operative relation with said escapement wheel.

5. In a typewriter, escapement mechanism

comprising an escapement wheel, a stop for preventing reverse movement of said escapement wheel, and a dog rocker on which said stop is mounted, said stop being movable relative to said dog rocker in the direction of movement of said escapement wheel and also transversely thereto.

6. In a typewriter, escapement mechanism comprising an escapement wheel, a dog rocker, dogs thereon for controlling the rotation of said escapement wheel, a stop on said dog rocker for preventing reverse rotation of said escapement wheel, said stop pivoted to move in a direction parallel to the plane of said escapement wheel and also transversely to the plane of said escapement wheel, and a spring for holding said stop in operative relation with said escapement wheel.

7. In a typewriter, escapement mechanism comprising an escapement wheel, dogs for controlling the rotation of said escapement wheel, a dog rocker for actuating said dogs, a universal member arranged to strike said dog rocker to impart oscillation thereto, stops for limiting the movement of said dog rocker, and separate stops for limiting the movement of said universal member.

8. In a typewriting machine, escapement mechanism comprising a dog rocker, a universal member for actuating said dog rocker, stops for limiting the movement of said universal member, stops for limiting the movement of said dog rocker independently of said universal member, and a power actuated device for actuating said dog rocker independently of said universal member.

9. In a typewriting machine, escapement mechanism, a power drive, means for connecting said power drive with said escapement mechanism to produce letter space movement, a control for said connecting means, a hand lever for operating said control, means for operating said escapement mechanism from said hand lever, said control being movable out of operative relation with said hand lever to permit operation of said escapement mechanism by said hand lever independently of said power drive.

In testimony whereof I have signed my name to this specification on this 7th day of May, A. D. 1924.

OTTO A. HOKANSON.
